UNITED STATES PATENT OFFICE.

WALTER CLAUDE JOHNSON, OF COLEMANS HATCH, ENGLAND.

FENCING.

1,269,819.

Specification of Letters Patent. Patented June 18, 1918.

Application filed April 13, 1917. Serial No. 161,736.

To all whom it may concern:

Be it known that I, WALTER CLAUDE JOHNSON, subject of the King of Great Britain, residing at Broadstone Farm, Colemans 5 Hatch, Sussex, England, have invented new and useful Improvements in Fencing, of which the following is a specification.

This invention relates to an improved construction of continuous fencing consisting 10 of wooden staves secured at intervals to bendable longitudinal strips, the assembled components being adapted to be rolled into a bundle convenient for transportation to the place of erection.

15 In fencing of such a character, as hitherto constructed, the flexible longitudinal member has consisted of double wires twisted around each other in a manner to provide loops within which the wooden staves are 20 secured. In such a method of construction the staves and the longitudinal flexible member of the fencing are inseparable whereas, according to the present invention the staves, which constitute the chief bulk and 25 mass of the fencing, can be provided locally and the components of the fence assembled either *in situ* or in the immediate neighborhood of the place of erection.

According to the present invention the 30 flexible longitudinal component consists of a bendable strip of metal which is perforated at intervals for the insertion of wire fastenings or provided at intervals with notches for the engagement therewith of 35 bendable fastening clips as represented in the accompanying drawings which show alternative details of construction.

In these drawings:

Figures 1 and 2 show how the staves and 40 the longitudinal strip are secured together by wire fastening elements.

Figs. 3, 4, 5 and 6 show how the fastening element consists of a bendable clip, Fig. 3 being the profile of the clip as stamped 45 from sheet metal, Fig. 4 a plan, Fig. 5 a side elevation and Fig. 6 a front elevation.

Figs. 7, 8 and 9 represent a modified construction of the same type of clip.

Fig. 10 is one view of a further modification.

Fig. 11 is an elevation on a smaller scale showing portions of fencing assembled and

erected by means of the clip fastenings illustrated in the preceding figures.

Referring to Figs. 1 and 2 the longitudinal strip A is perforated by equidistant holes or cavities a, a, large enough to receive a short length of wire fastening C inserted as shown in dotted lines in Fig. 2.

A stave B is secured to the strip A by assembling them as shown in Fig. 2 in full lines in such a manner that the wire C is bent to embrace the stave and the ends twisted around one another. By such means the staves may be spaced near together or 65 far apart as desired.

According to Figs. 3-6 the fastening element consists of a clip piece D stamped to a cross profile from bendable metal as shown in Fig. 3 the long arms d¹, perforated near 70 their extremities, being of such a length as to embrace the stave and cause the two holes at their extremities to become coincident and enable a nail E to be driven through both into the stave B as shown in Figs. 4 and 5. 75 The shorter arms d² d² are of such a length as to clasp the longitudinal strip F at the portion where a notch or cavity f is formed as shown in Figs. 5 and 6. The notch may be formed on one only of the edges of the 80 strip or on both edges as indicated in Fig. 11. The notch f serves to prevent longitudinal displacement of the clip fastening D along the strip F.

To enable the clip fastening to closely embrace staves of varying girth, the cross shaped clip-piece may be somewhat modified as shown by G in Fig. 7 and bent to embrace the stave as shown in Figs. 8 and 9 enabling each arm g¹ to be separately nailed 90 to the stave.

According to a further modification the extremities of the longer arms of the cross-shaped clip-piece may be bent hook-shaped as shown in Fig. 10 and secured together by 95 wire and thus obtain a tighter embrace of the stave.

I claim:

1. A fence comprising spaced vertical staves, flat strips spanning the staves and 100 elongated fastening elements embracing the staves and having medial extensions embracing the strips.

2. A fence comprising spaced vertical

staves, flat strips spanning the staves and formed at intervals with notches, and elongated fastening elements embracing the staves and having medial extensions embracing the strips and engaging said notches to prevent longitudinal as well as vertical movements of the strips with respect to the staves.

In testimony whereof I have signed my name to this specification in the presence of 10 two subscribing witnesses.

WALTER CLAUDE JOHNSON.

Witnesses:

ROBT. A. BLAKE,
F. W. LANE.
